OSCAR SCHWIMMER, OF LOS ANGELES, CALIFORNIA, ASSIGNOR TO J. J. NEWELL, OF LOS ANGELES, CALIFORNIA.

TOWEL-OPERATING MECHANISM.

1,274,611.

Specification of Letters Patent.

Patented Aug. 6, 1918.

Application filed July 31, 1916, Serial No. 112,440. Renewed June 5, 1918. Serial No. 239,881.

To all whom it may concern:

Be it known that I, OSCAR SCHWIMMER, a citizen of the United States, residing at Los Angeles, county of Los Angeles, and 5 State of California, have invented a certain new and useful Improvement in Towel-Operating Mechanism, of which the following is a specification.

My invention relates to a towel cabinet 10 for exposing for use a definite portion of a continuous strip of toweling contained therein, and has especial reference to a simple means for accomplishing the winding up of a strip of toweling, an object of this 15 invention being to provide a mechanical combination wherein the take-up of the used portions of toweling may be effected automatically as the diameter of the roll increases, or in other words, to govern the distance of rotation of the take-up roller proportionately with the diametrical increase 20 of the toweling on the roller.

These and other objects are accomplished by the device shown in the accompanying 25 drawing, and specially pointed out in the claims.

Figure 1 is a fragmentary front view showing my invention as applied,

Fig. 2 is a side view of the mechanism, and 30 Fig. 3 shows a modified form of towel operating device.

My invention comprises generally a cabinet in which is contained a roll of toweling, a portion of which is exposed and remains 35 exposed for use as long as the clean toweling is not exhausted, and the presentation of a new length of clean toweling with the concurrent take-up of the used portion is effected by a single lever operable by the 40 user.

Specifically my invention includes a cabinet 1, or other container, having a door 2, on which the entire mechanism is arranged to be mounted.

45 In a bracket 3, on said door 2, is supported a roller 4, on which a length of toweling 5 is wound. Said roller 4, may be frictionally held against free and independent movement by a band 6. One end of said 50 roller 4 is provided with a ratchet-wheel 7, with which a pawl 8, is arranged to cooperate to lock the roller against movement, as will appear hereinafter.

Below the bracket 3, is a frame 9, in which 55 is journaled three rollers 10, 11, and 12, the

first and last of which are preferably held in position by a yielding means, as at 13, to enable the same to respond to any irregularities in the toweling 5, that is drawn between said rollers.

60 The door 2 is provided with openings 14 and 15, through the former of which the toweling passes after being drawn between the rollers 10 and 11, and through the latter of which the toweling enters the cabinet, a 65 determinate amount of slack being left exposed to form a loop 16, for a user of the toweling.

The toweling 5, after leaving the rollers 11 and 12, is taken up on a roller 17, journaled in a bracket 18, below said frame.

70 The rollers 10, 11 and 12, are each provided on one end with gears 19, 20 and 21, that intermesh, the central roller being also provided with a pinion 22 meshing with a 75 gear wheel 23 on the frame 9. Integral with said gear wheel 23, is a ratchet wheel 24, arranged to be operated by a pawl 25, which is carried on a plate 26, pivotally mounted on the same journal as the gear 23 and 80 ratchet wheel 24.

85 On said plate 26, is a stud 27, for pivoting a link 28, whose upper end is provided with a slot 29, through which is extended an arbor 30, on a lever 31, that forms the main operating member. Said arbor 30, forms also a pivotal bearing for a link 32, pivotally connected to the end of said afore-mentioned pawl 8. The lever 31, is pivoted at one end in an extension 33, of said frame 9, 90 and the other end extends out beyond the face of the door 2, to afford a handle 34 for the operator.

95 The operation of the take-up roller 17, is effected concurrently with the operating movement of the lever 31, and through the medium of a member 35, which may comprise a tubular body 36, pivotally attached to said lever 31. Operating in said tubular body 36, is a rod 37, held against disassociation from said body 36, by a pin 38 that extends through the upper end of said rod and operates in slots 39 in said body.

100 On said tubular body 36, is a collar 40, and on the rod 37, is a collar 41, said collars forming abutments for an expansion spring 42. Onto the lower end of the rod is pivotally secured a pawl 43, straddling a ratchet wheel 44 on said take-up roller 17, and serving to operate same. A spring 45 functions 110

to hold said pawl 43 in position for engagement with the ratchet wheel 44, and a spring 46 may be used to lock said member 35 in operative position. The ratchet wheel 44 5 may be engaged by a dog 46' to prevent reverse movement of the take-up roller.

The operation of the device is substantially as follows:

As the lever 31 descends, it engages the 10 link 32 which releases the pawl 8, from the ratchet wheel 7, leaving the supply roller 4 free to revolve. Simultaneously, the arbor 30 is moved to the bottom of the slot 29 in link 28. Thereupon on further downward 15 movement of said lever 31, the link 28 is depressed, causing, through the plate 26, the pawl 25 to engage and operate the ratchet wheel 24, whereby the gear wheel 23 is revolved, and through whose revolution, motion 20 is transmitted to the rollers 10, 11 and 12, through their gears.

As the rollers 10 and 11 are revolved, a supply of toweling is drawn from the supply roll 4, and fed through opening 14, the 25 used toweling being drawn through the opening 15 in the door 2, by means of the rollers 11 and 12. When the lever 31 is being moved downwardly, it carries with it the member 35, the lower end 42, of which 30 engages and operates the ratchet wheel 44 on the take-up roller 17. Thereby the take-up roller 17 is revolved for a distance equal to the length of the used toweling as fed. As the diameter of the rolled toweling in- 35 creases, so will also its surface extent increase proportionately to the accumulation of toweling, and such increase in surface extent would, with each depression of the lever, require more toweling than that pass- 40 ing through the rollers 10, 11 and 12, hence it is necessary to provide for regulating the revolution of the take-up roller proportionately with the feed, and this is accomplished by the member 35, the rod 37 of which, while 45 sufficiently strong to wind the used toweling upon the roller, will yield for the balance of the downward movement of the handle or operating lever 31.

The dog 46' falls into place on the ratchet 50 wheel 44 and retains said roller in position. Upon the return of the lever to normal position, under the tension of a spring 47, the pawl 8 returns to locking position on the ratchet wheel 7.

In Fig. 3, a form different from the roller 55 feed shown in Fig. 2, is illustrated. The modification consists of a walking beam 48, formed on the top and bottom with a shelf 49, between which and a pawl member 50 the toweling is run. Oscillatory motion is given 60 to said walking beam by a lever 51, which is connected with said beam by a link 52, and by such oscillatory motion the toweling is advanced and pulled back into the case.

What I claim, is:—

1. A towel cabinet having a plurality of slots therein, a toweling roller therein, a plurality of rollers for drawing and passing the toweling through one of said slots and returning the toweling through the other of 70 said slots, a take-up roller for used toweling, means for operating all of said rollers simultaneously, and a yieldable rod connected with said roller operating means for regulating the travel of said take-up roller 75 as the diameter thereof increases.

2. A towel cabinet having a plurality of slots therein, a toweling supply roller therein, a plurality of rollers for drawing and passing the toweling through one of said 80 slots and returning the toweling through the other of said slots, geared means to operate said rollers, a lever to operate said geared means, a take-up roller for used toweling, and a yielding means connected to 85 and operable by said lever for moving said take-up roller a distance sufficient only to take up the used portion of toweling.

3. A towel cabinet having a plurality of slots therein, a toweling supply roller therein, a plurality of rollers for drawing and passing the toweling through one of said slots and returning it through the other of 90 said slots, geared means to operate said rollers, means connecting the top and lower 95 roller to enable same to yield to unevenness in the toweling, a lever to operate said geared means, a take-up roller in the bottom of the cabinet, and a yielding means controllable by the operation of said lever for regulating the travel of said take-up roller as the diameter thereof increases.

In testimony whereof I affix my signature in the presence of two witnesses.

OSCAR SCHWIMMER.
